HYDRAULIC LOG BARKER WITH TRAVELING JET AND AUTOMATIC AND MANUAL CONTROLS

Herbert W. Guettler, San Francisco, Calif.

Application March 26, 1949, Serial No. 83,590

10 Claims. (Cl. 144—208)

1

This invention relates to apparatus for removing the bark from logs, and has to do with apparatus in which the removal of the bark is accomplished by a high pressure water jet projected against the log.

It is known to remove the bark from logs by means of a nozzle which projects a high pressure jet of water against the log, this nozzle being moved lengthwise of the log during rotation thereof. It is also known to bark short logs by means of a high pressure water jet projected against the log and extending the full length thereof, during rotation of the log. In another form of hydraulic barking apparatus, high pressure water jets are projected against the log generally lengthwise thereof, from a nozzle structure surrounding the log and through which the log is moved lengthwise during the barking operation. In hydraulic barkers employing a nozzle travelling lengthwise of the log, it is necessary to provide flexible connections of considerable length for supplying the water under pressure to the nozzle, which incurs difficulties and expense in respect to leakage and necessary repairs, aside from the expense of the travelling nozzle carriage, the means for driving the carriage and associated features. The known apparatus for barking logs by projecting against the log a high pressure water jet extending the full length of the log during rotation thereof is suitable for barking short logs only since a nozzle structure of considerable length, such as would be required for long logs, incurs difficulty in respect to maintaining the required high pressure throughout the full length of the nozzle structure. In the known apparatus in which the log is moved lengthwise through an annular nozzle structure, the width of the apparatus must be at least twice the length of the logs handled. That is objectionable, particularly where logs of considerable length are to be barked, in that the apparatus of necessity occupies an objectionable amount of space.

My invention is directed to a log barker which avoids the referred to objections to the above mentioned known hydraulic barkers. To that end, I provide a barker the overall width of which need be but slightly greater than the maximum length of logs intended to be handled by such barker, and in which the barking operation is effected by a nozzle head which is stationary lengthwise of the log. In conjunction with the nozzle head I provide means whereby a high pressure water jet is projected against the log while the latter is rotated, this jet being of slight extent lengthwise of the log and traveling there-

2

along from one end to the other, effective for removing the bark throughout the whole length of the log. The nozzle head comprises a plurality of nozzles each having a jet opening for projecting a high pressure water jet against the log, these nozzles having associated therewith means whereby water under appropriate pressure may be admitted to the nozzles selectively, successively in desired order, or simultaneously, as desired. Accordingly, the barker of my invention is well suited for removing bark from the log throughout the whole length thereof, by means of a traveling jet, as above mentioned, or may be used for removing from a log adhering patches of bark not previously removed in the barking operation performed in some other apparatus, such as a barking drum, or it may be used for subjecting the log to a continuous high pressure water jet extending the full length of the log, when desirable. As will be understood from what has been said, the barker of my invention provides a novel and highly efficient method of barking logs, to which method my invention is also directed. Further objects and advantages of my invention will appear from the detail description.

In the drawings:

Figure 1 is a plan view of a hydraulic log barker embodying my invention, the log decks being partly broken away and certain of the logs on the transfer deck being partly broken away;

Figure 2 is a side view of the apparatus of Figure 1, with certain parts broken away;

Figure 3 is a sectional view, taken substantially on line 3—3 of Figure 2, certain parts being shown in elevation;

Figure 4 is a vertical sectional view, on an enlarged scale, of one of the nozzles and its associated valve, taken from front to back of the nozzle, this view also showing in elevation the valve operating means;

Figure 5 is a fragmentary lengthwise sectional view, on an enlarged scale, of the nozzle head showing its relation to the log, which is shown fragmentarily in elevation;

Figure 6 is a diagram of the solenoid valves for controlling the nozzles and of the rotary switch and the manually operated switches for operating the solenoid valves, this view showing the electrical circuits for the motor driving the rotary switch and for the solenoid valves; and

Figure 7 is a diagram illustrative of the order in which the solenoid valves are operated by the rotary switch.

55 The log barker of my invention comprises a

transfer deck 15 and a receiving deck 16 supported by a suitable framework on a base or foundation 17. The deck 15 is of known construction and comprises channel members 18 receiving chains 19 by means of which logs 1' to be barked are moved inward over the deck 15. The chains 19 pass about sprockets 20 on a cross shaft 21 rotatably mounted in bearing blocks 22 secured to a cross channel 23 at the inner end of deck 15. The chains 19 are driven in any suitable known manner, which need not be described in detail here.

A cross rod 24 is mounted in brackets 25 mounted on the supporting framework of the deck structure. The cross rod 24 receives several log loaders and stoppers 27 rockably mounted thereon at about their mid-length and curved or arched downwardly, as shown more clearly in Figure 2. The outer ends of the log loaders and stoppers 27 are connected together by a rod 28 secured therethrough. This rod 28 is attached, at its mid-length, to the upper end of a piston rod 29 by means permitting relative turning between the rods 28 and 29, conveniently by a collar at the upper end of rod 29 through which the rod 28 passes. The piston rod 29 passes through a stuffing box 30 at one end of a cylinder 31 pivoted at its other end, at 32, to a bracket 33 anchored to base 17. The rod 29 is attached at its lower end to a piston (not shown) operating in the cylinder 31, as will be understood.

The cylinder 31 is provided with upper and lower ports connected by flexible high pressure conduits or hose sections 34 and 35 to two ports of a solenoid valve 36 of known type mounted on an upright 37 of the frame structure. The solenoid valve 36 is also provided with an inlet port connected by a conduit 38 to a suitable source of supply of operating fluid under pressure, and is further provided with an exhaust port (not shown). Preferably, I employ steam under appropriate pressure for operating the piston in cylinder 31. Normally, the solenoid valve 36 is de-energized, with the inlet port thereof open and the outlet or exhaust port in communication with the flexible tube or conduit 35 leading from the lower end of cylinder 31. A piston in cylinder 31 is then held under pressure at the lower end of this cylinder, effective for holding the log loaders and stoppers in their stop position shown.

A suitable number of log skids 40, slotted from their inner ends, are mounted on the cross rod 24 and are inclined downward and inward therefrom, these skids 40 being restrained against downward movement by angle stops 41 secured on uprights of the frame structure. These skids 40 straddle corrugated rolls or disks 42 secured on a shaft 43 rotatably mounted in bearing blocks 44 secured to channel members 45 connecting uprights 31, adjacent the inner end of the deck 15, to uprights 47 adjacent the inner end of deck 16. The disks or drums 42 are aligned with similar disks or drums 48 fixed on a shaft 50 disposed in parallel spaced relation to shaft 43 and rotatably mounted in bearing blocks 51 secured to the channel members 45. The disks or drums 42 and 48 thus are arranged in pairs and define between them, in effect, a downwardly diverging trough-like recess or depression for reception of a log to be barked, as will appear more clearly from Figure 2.

A sprocket wheel 53 is fixed upon one end of shaft 43, in alignment with a similar sprocket wheel 54 fixed on the corresponding end of shaft 50. A sprocket chain 55 passes about the sprocket

wheel 53 and 54 establishing driving connections therebetween. A multiple grooved V-pulley 56 is fixed on shaft 50, adjacent sprocket wheel 54, and receives a plurality of V belts 57 passing about a multiple grooved V-pulley 58 secured on the drive shaft of a speed reducer 59 of known type driven by an electric motor 60 of suitable known type. The motor 60 is controlled by a rheostat and a reversing switch whereby it may be reversed and may be driven at any desired speed, within limits, for driving the shaft 50 in desired direction and at desired speed. Assuming that the pulley 56 is driven in clockwise direction, as viewed in Figure 2, the sprocket wheels 53 and 54 will also be driven in clockwise direction and a log 1' resting upon the disks 42 and 48 will be rotated about its axis in counterclockwise direction.

A suitable number—three are shown—of unloader sectors 62 are rockably mounted on the shaft 50. These sectors 62 are connected together by a rod 63, adjacent their lower ends. This rod 63 is suitably connected, at its mid-length, to the upper end of a piston rod 64 passing through a stuffing box 65 at the upper end of a cylinder 66 pivoted at its lower end, at 67, to a bracket 68 anchored to the base 17. As will be understood, the piston rod 64 is attached to a piston operating in the cylinder 66 for imparting movement to the unloader sectors 62 in desired directions. The cylinder 66 is provided with ports adjacent its ends connected by flexible conduits or hose lengths 70 and 71 to ports of a solenoid valve 72 having an inlet port connected by a conduit 73 to a source of supply of pressure fluid, conveniently a liquid such as water. The valve 72 is also provided with an outlet or exhaust port. When the valve 72 is energized, it is effective for admitting water under high pressure to the cylinder 66 through conduit 71, while permitting escape of water from cylinder 66 through the conduit 70. Accordingly, when the solenoid valve 72 is energized the piston rod 64 is projected and swings the unloader sectors 62 in clockwise direction about shaft 50. This movement of the sectors 62 displaces the log 1' from the disks 42 and 48 and delivers it to skids 75 suitably secured to the framework of deck 16, these skids being slotted at their inner portions and straddling the disks 48. In that manner, the barked logs are delivered to the deck 16 and are conveyed by the chains 76 thereof to a suitable point of discharge, as is known. When the solenoid valve 72 is de-energized, water under appropriate pressure is admitted to the cylinder 66 through the conduit 70, and water is discharged from the cylinder 66 through conduit 71. In that manner, the unloader sectors 62 are returned to their normal inoperative position shown in Figure 2 and are held in that position during the removal of the bark from the log under treatment. It will be understood that the solenoid valve 72 is controlled by a suitably located switch, in the same manner as the valve 36, as will be explained more fully later.

A suitably constructed frame 80, of rectangular shape in plan, is anchored to the deck framework and extends upward an appropriate distance thereabove, the top structure of this frame overlying the log receiving space or trough between the disks 42 and 48. Two vertical columns 81 are secured in frame 80, one adjacent each end thereof. These columns 81 slidably receive a nozzle head frame 82 comprising upper and lower channel members 83 and 84 connected together.

by end bars 85 and provided with guide sleeves 81. A reversible low speed electric motor 86 of suitable known type is mounted on the top of frame 80 at the mid-length thereof. A double grooved pulley 87 is secured on shaft 86a of motor 86. Two belts 88 one of which is crossed, are passed about pulley 87, respectively seating in the grooves thereof. Each of the belts 88 passes about a pulley 89 secured on a cross shaft 90 carried by brackets 91 secured to the top of frame 80 adjacent each end thereof. Two cables 88a respectively pass over sheaves 96a also secured on the shafts 90. One run of each cable 88a passes downward about a sheave 92 rotatably mounted on a cross shaft 93 mounted in brackets, one of which is shown at 94, secured to the bottom of frame 80 at the end thereof. From the sheave 92 the cable 88a passes upward and is anchored to channel member 84. The other run of cable 88a passes from sheave 96a downward to channel member 83, to which it is anchored. As will be understood, the two cables 88a are connected to the nozzle head frame in the same manner. It will be apparent that by driving the motor 86 in appropriate direction, the nozzle head frame 82 may be adjusted vertically in either direction and to desired extent. The motor 86 is controlled by a rheostat and a reversing switch suitably located for ready access in the operation of the apparatus. Within the broader aspects of my invention, vertical adjustment of the nozzle head frame 82 may be effected in any suitable manner.

The lower channel member 84 of the nozzle head frame 82 has mounted thereon a plurality of nozzles 96, the assembly constituting a nozzle head. Each of the nozzles 96 comprises a body 97 of rectangular shape in front or back elevation, with the front and back walls thereof converging downward and defining between them, at their lower edges, a restricted jet opening 99 (Figure 4) extending the length of body 97, between the end walls 99 thereof. The nozzles 96 are disposed in juxtaposed relation, preferably with their end walls in contact, and the inner face of each end wall 99 of the respective nozzles 96 is inclined downward and outward. This inclination of the inner surface of end wall 99 is such that there is an appreciable overlap between the jet areas of adjacent nozzles 96, as will be explained more fully later. Each of the nozzles 96 is provided, at the top thereof, with a central neck 100 provided at its upper end with a circumferential flange 101. This flange 101 receives a similar flange 102 seating thereon, at the lower end of a neck 103 of a valve 104. The flanges 101 and 102 provide means for securing the nozzles 96 in assembled relation on the channel member 84 of frame 82, while also securing the valves 104 to the nozzles 96.

The valve 104 is of known type and comprises a cylindrical valve member 105 extending into the body of valve 104 and slideable through a stuffing box 106 at the upper end of valve 104. This valve member 105 is provided with ports 107 adjacent its lower or inner end, and controls communication between neck 103 and a neck 109 extending from the body of valve 104 perpendicular to neck 103. The neck 109 is provided at its outer end with a circumferential flange 110 for bolting to a flanged fitting 111 to which is appropriately secured one end of a flexible high pressure conduit or hose length 112 connected to a suitable source of water under a pressure of appropriate value. The pressure used may vary considerably, depending upon the kind

and condition of the logs being barked. In general, the pressure may be from 500 to 3000 pounds per square inch, though the limits stated may be exceeded in either direction as conditions may require.

Referring further to Figure 4, the valve member 105 is secured to the lower end of a piston rod 114 passing through the lower head of a cylinder 115, the upper end of rod 114 being secured to a piston (not shown) operating in the cylinder 115. The cylinder 115 is suitably secured to the upper channel member 83 of the nozzle head frame 82 and is provided with upper and lower ports connected by short tubes 116 and 117, respectively, to two ports of a solenoid valve 118 suitably mounted on channel member 83. The valve 118 is further provided with an inlet port connected by a high pressure conduit 120, which may include a length of flexible high pressure hose (not shown), to a suitable source of water under appropriate pressure. The solenoid valve 118 is also provided with an outlet port connected by a conduit 121 to a suitable point of discharge. The solenoid valve is of known type and, when energized, is effective for admitting water or other operating fluid under pressure to the cylinder 115 through the tube 117, while permitting escape of fluid from the cylinder 115 through the tube 116. Energizing of the solenoid valve 118 thus effects movement of the valve member 105 into its upper open position shown in Figure 4, for admitting water under pressure to the nozzle 96. When the solenoid valve 118 is de-energized, pressure fluid is admitted to the cylinder 115 through tube 116 and pressure fluid escapes from the cylinder 115 through the tube 117. The valve member 105 is then moved downward into closed position, effective for cutting off the supply of water to the nozzle 96.

It will be understood, from what has been said, that each of the cylinders 115 is provided with a solenoid valve 118. In Figure 3 I have shown twelve nozzles 96 mounted on the lower channel member 84 of frame 82 and together constituting the nozzle head. Referring to Figure 6, the solenoid valves 118 may be energized successively by a rotary cam switch 125 of known type. The switch 125 comprises a suitably insulated shaft 126 carrying contact members or cams 127 which cooperate with fixed contact members 128. The shaft 126 is driven by a power unit comprising a speed reducer R and an electric motor M of suitable type, such unit being indicated by the reference number 129. The motor of the unit 129 is controlled by a reversing switch 130 and a rheostat 131, whereby the direction of drive and the speed of rotation of shaft 126 may be adjusted as required. A conductor 133, connected to one side of a suitable source of electrical energy, is electrically connected to the shaft 126 in a suitable known manner, as by means of a brush contacting the shaft. The contact members 128 are respectively connected by leads 134 to one side of the respective solenoid valves 118. Each of the leads 134 has interposed therein a switch 135 which may be operated in any suitable manner, the switch shown being indicated as a hand operated switch. The other side of the coil of the respective solenoid valves 118 is connected by a lead 136 to a second conductor 137 connected to the other side of the source of electrical energy. It will be seen that when the switch 125 is in operation, the cams or contact members 127 thereof will cooperate with the contact members 128 for

energizing the operating coils of the solenoid valves 118.

Referring to Figure 7, the contact cams 127 of switch 125 are so disposed that they engage the contact members 128 successively from one end of the switch to the other end thereof. The speed of rotation of shaft 126 is such that each cam 127 maintains contact with the corresponding contact member 128 for a period of time corresponding to the time required for turning the log being barked through one complete rotation, as will be explained more fully presently. During one complete rotation of shaft 126, the solenoid valves 118 are successively energized, it being assumed, for purposes of description, that the valves 118 are energized in the order in which they are numbered, that is, from right to left in Figure 6. After the last or twelfth valve 118 has been energized, there is a predetermined lapse of time, preferably corresponding to the time for which each of the solenoid valves is energized, during which none of the valves is energized, this inactive period being indicated by the sector s on the diagram of Figure 7. In this Figure 7 diagram, the numbered sectors indicate the contact members or cams 127 of the switch 125 and the time periods during which the cams close the energizing circuits of the respective solenoid valves 118. As indicated on the diagram, as one cam 127 of switch 125 passes out of contact with the corresponding contact member 128, the next cam 127 enters into contact with the corresponding stationary contact 128.

It may be assumed, for purposes of description, that the log being barked is turned through one complete rotation in two seconds. Under the conditions stated, the cam switch 125 should be driven at such speed that each of the cams 127 thereof maintains contact with the corresponding stationary contact member 128 for a period of two seconds. Assuming that the log to be barked is properly positioned upon the discs or rollers 42 and 48 and is being rotated at the speed stated, the switch 125 closes the circuits of the solenoid valves 118 in the order in which such valves are numbered in Figure 6, and maintains the circuit of each valve closed for a period of two seconds. When the circuit of the first solenoid valve is closed, a high pressure water jet is projected from the corresponding end nozzle 96 of the nozzle head against the log, this jet being in the form of a thin sheet which readily splits the bark of the log. As the log rotates the water jet removes the bark throughout the full circumference of the log and for a distance lengthwise thereof corresponding to the length of the jet. As the log completes one rotation, the supply of water to the first nozzle is cut off and water is admitted under high pressure to the second nozzle and so on. I thus provide means whereby a high pressure water jet of slight length relative to the total length of the nozzle head is caused to travel from one end of the log to the other end thereof while the log is continuously rotated, whereby the log is barked throughout its full length. Under the conditions assumed, the log would be completely barked in approximately twenty four seconds. By employing a traveling jet in the manner stated, the nozzle head may remain stationary, horizontally or lengthwise of the log under treatment, which is conducive to simplicity of construction and operation as well as to high efficiency. As previously noted, the jets from adjacent nozzles overlap, as shown in Figure 5, in which it is assumed, for purposes of illustration,

that four adjacent nozzles are in operation simultaneously, which ordinarily is not the case.

The effective length of the nozzle head is somewhat greater than the maximum length of logs which it is contemplated will be barked in the apparatus. That assures barking of the log for the full length thereof. By means of the apparatus so far described, logs of considerable length, such as twenty feet or over in length, may be barked thoroughly and cleanly within a comparatively short time. After the last nozzle of the nozzle head assembly has been put into operation, completing the barking of the log, all of the nozzles remain closed for a period of time represented by the sector s on the diagram of Figure 7, as above explained. During that time, the unloader sectors 62 are operated for transferring the barked log to the deck 16 in the manner previously described, and the loaders and stoppers 27 are operated for delivering to the rollers or discs 42 and 48, from deck 15, a log to be barked. Those operations are quickly performed so that a succeeding log is positioned beneath the nozzle head and is being rotated when the No. 1 solenoid valve 118 is again energized. The operation of the apparatus is thus largely automatic and substantially continuous so that no time is lost, rendering possible comparatively great output.

As above indicated, the apparatus of my invention is particularly suitable for barking logs of large size which cannot be handled to advantage in barking drums or like apparatus. In many instances, smaller logs can be barked to better advantage in barking drums or other known types of barking apparatus. It frequently happens, however, that logs so treated are not completely barked and have adhering patches of bark which must be removed. The apparatus of my invention is particularly suitable for treating such incompletely barked logs. Referring further to the diagram of Fig. 6, the switches 135 normally are closed. By opening selected ones of the switches 135, only those nozzles 96 corresponding to the switches 135 which remain closed will be operated responsive to operation of the rotary switch 125. Accordingly, the nozzles may be selectively operated so as to project water jets against only those areas of the log having adhering patches of bark. That is advantageous as it effects a saving in time as well as in water. In that connection, the operator may set the rotary timer switch 125, while a log is being loaded onto the discs 42 and 48, so as to actuate only those nozzles 96 which are to be used, thus avoiding, in many cases, necessity for operating switch 125 through a complete cycle. Further, logs much shorter in length than the nozzle head may be barked for their full length by utilizing only those nozzles extending the length of the log to be barked, again effecting a saving in time and in water.

I have provided a lead 140 extending from conductor 133 and connected to all of the leads 134, between the switches 135 and the solenoids 118, through switches 135a. The lead 140 has interposed therein a switch 141 of suitable type, shown for purposes of illustration as a manually operated switch. The switch 141 normally is open, as are the switches 135a.

When it is desired to remove from an incompletely barked log a patch of bark of considerable length, or several patches of bark, the appropriate nozzles 96 may be employed for that purpose. In such cases, the rotary switch 125 is stopped in its open position, placing the nozzles

96 under control of switch 141, which remains in its open position, and the switches 135^a, all of which are then open. The switch 141 is then closed, after which the switches 135^a corresponding to the nozzles 96 which it is desired to use are closed, either successively or simultaneously, as desired. The nozzles 96 which are used are, of course, those which are disposed to project the water jets against the areas of the log at which the patches of adhering bark are located. Alternatively, all of the switches 135^a corresponding to the nozzles 96 which it is desired to use may remain closed, the remainder of the switches 135^a being open, preliminary to closing of switch 141. Then when switch 141 is closed, the nozzles 96 corresponding to the closed switches 135^a will be put into operation simultaneously. In either case, only those nozzles required for removing the adhering bark from the incompletely barked log will be utilized, thereby effecting a corresponding saving in water and in time.

Under certain conditions, it may be desired to place all of the nozzles into operation simultaneously. By closing switch 141, with all of the switches 135^a closed, all of the solenoid valves 118 may be energized simultaneously, independently of the rotary switch 125, thus providing a continuous high pressure water jet extending the full length of the nozzle head. That may be desirable in certain cases, where it is important that a log be completely barked or subjected to the high pressure water spray throughout its full length in the quickest possible time. Normally, however, I prefer to use the spray of slight length relative to the nozzle head and traveling lengthwise of the log, since assurance is had that the spray impacts the log under adequately high pressure to assure thorough and quick barking thereof. From what has been said, it will be seen that the nozzles of the nozzle head may be operated successively, selectively, and simultaneously, either under control of the rotary switch 125 or under manual control, as desired or as conditions may require.

A control station 63 is provided at one side of the machine, from which station the operator can view the debarking operation. This station may be provided with a panel 145 upon which may be placed the various switches and rheostats as well as other instruments, for regulating and controlling operation of the apparatus in the manner above described. Obviously, the control station may be located at any suitable position, and the control switches and other instruments may be suitably disposed at one or more locations as conditions may dictate.

I have shown, in Figure 3, twelve nozzles 96 comprising the nozzle head, each having a length equal to one twelfth of the head, and have referred to the nozzle as being of slight length relative to the head, and to the water jet from a single nozzle as being of slight length relative to the length of the log under treatment. It will be understood that the length of the respective nozzles and the length of the water jet from a single nozzle may be varied. In general the length of the nozzle may be from one twelfth, or less, to a substantial fractional part of the length of the nozzle head, and the length of the water jet from a single nozzle may vary within the same limits, relative to the length of the log under treatment. Accordingly, the term "slight length" as used herein is to be construed as meaning a fractional part of the length of

the nozzle head or of the log under treatment, in respect to both the nozzle and the water jet from a single nozzle. From what has been said, it will be clear that the log is not moved lengthwise during the barking operation. The logs are quickly and completely barked by subjecting them to a high pressure water jet from a stationary nozzle head during rotation of the log. In the method of my invention the log, during rotation thereof and without lengthwise movement, is thus subjected to the action of a plurality of high pressure water jets successively lengthwise of the log, each of a length but a fraction of the length of the log and stationary lengthwise thereof, with the effective area of each jet overlapping the effective area of the next preceding jet. That avoids necessity for moving the log lengthwise, or for moving the nozzle head lengthwise of the log, with the advantages above noted.

As above indicated, changes in detail may be resorted to without departing from the field and scope of my invention, and I intend to include all such variations, as fall within the scope of the appended claims, in this application in which the preferred form only of my invention has been disclosed.

I claim:

1. In a hydraulic log barker, means for supporting a log to be barked in substantially horizontal position and rotating it about its axis at predetermined speed and without endwise movement, a substantially horizontal nozzle head remaining stationary horizontally and being provided with a plurality of jet openings arranged in a series lengthwise of said head, said openings being respectively disposed to project a high pressure water jet against the log and of fractional length relative to the total length of said head, and means comprising valves individual to said jet openings and timer control means therefor effective for automatically admitting water under high pressure to said jet openings successively, the time period of admission of water to the respective openings being approximately the same as the time period required for one complete rotation of the log.

2. In a hydraulic log barker, means for supporting a log to be barked in substantially horizontal position and rotating it about its axis at predetermined speed and without endwise movement, a nozzle head overlying said means substantially parallel therewith and being adjustable vertically and restrained against horizontal movement, said head comprising a plurality of juxtaposed nozzles respectively provided with a jet opening disposed to project against the log a high pressure water jet extending lengthwise thereof with the areas of the jets from adjacent nozzles overlapping, valves individual to the respective nozzles and controlling admission thereto of water under pressure, and timer control means for operating said valves successively in timed relation to the rotation of the log and effective for producing a high pressure water jet traveling lengthwise of the log.

3. In a hydraulic log barker, means for supporting a log to be barked in substantially horizontal position and rotating it about its axis at predetermined speed and without endwise movement, a nozzle head overlying said means substantially parallel therewith and being adjustable vertically and restrained against horizontal movement, said head comprising a plurality of juxtaposed nozzles respectively provided with a jet

opening disposed to project against the log a high pressure water jet extending lengthwise thereof with the areas of the jets from adjacent nozzles overlapping, valves individual to the respective nozzles and controlling admission thereto of water under pressure, and means comprising timer control means and manual control means for operating said valves selectively and successively, optionally, in timed relation to the rotation of the log, successive operation of said valves being effective for producing a high pressure water jet traveling lengthwise of the log.

4. In a hydraulic log barker, means for supporting a log to be barked in substantially horizontal position and rotating it about its axis at predetermined speed and without endwise movement, a nozzle head overlying said means substantially parallel therewith and being adjustable vertically and restrained against horizontal movement, said head comprising a plurality of juxtaposed nozzles respectively provided with a jet opening disposed to project against the log a high pressure water jet extending lengthwise thereof with the areas of the jets from adjacent nozzles overlapping, valves individual to the respective nozzles and controlling admission thereto of water under pressure, and means comprising timer control means and manual control means for operating said valves selectively, successively, and simultaneously, optionally, in timed relation to the rotation of the log.

5. In a hydraulic log barker, means for supporting a log to be barked in substantially horizontal position and rotating it about its axis, a substantially horizontal nozzle head comprising a plurality of independent nozzles having jet openings arranged in a series lengthwise of said head and disposed to project a high pressure water jet against the log with the jet from each nozzle overlapping the jets from the next adjacent nozzles lengthwise of the log, control valves individual to said nozzles for cutting off and establishing supply of water under pressure thereto, and means for operating said valves comprising a timer switch effective for opening said valves successively lengthwise of said head for a predetermined time period and closing them successively lengthwise of said head.

6. In a hydraulic log barker, means for supporting a log to be barked in substantially horizontal position and rotating it about its axis, a substantially horizontal nozzle head comprising a plurality of independent nozzles having jet openings arranged in a series lengthwise of said head and disposed to project a high pressure water jet against the log with the jet from each nozzle overlapping the jets from the next adjacent nozzles lengthwise of the log, control valves individual to said nozzles for cutting off and establishing supply of water under pressure thereto, and means for operating said valves comprising a timer switch and switches individual to said valves whereby the latter may be operated selectively and successively lengthwise of said head while under control of said timer switch.

7. In a hydraulic log barker, means for supporting a log to be barked in substantially horizontal position and rotating it about its axis, a substantially horizontal nozzle head comprising a plurality of independent nozzles having jet openings arranged in a series lengthwise of said head and disposed to project a high pressure water jet against the log with the jet from each nozzle overlapping the jets from the next adjacent nozzles lengthwise of the log, control valves

5 individual to said nozzles for cutting off and establishing supply of water under pressure thereto, means for operating said valves comprising a timer switch effective for opening said valves successively lengthwise of said head for a predetermined time period and closing them successively lengthwise of said head, and manual control means for operating said valves independently of said timer switch comprising a main control switch connected in shunt with said timer switch and switches individual to said valves.

8. In a hydraulic log barker, means for supporting a log to be barked in substantially horizontal position and rotating it about its axis, a substantially horizontal nozzle head comprising a plurality of independent nozzles having jet openings arranged in a series lengthwise of said head and disposed to project a high pressure water jet against the log with the jet from each nozzle overlapping the jets from the next adjacent nozzles lengthwise of the log, control valves individual to said nozzles for cutting off and establishing supply of water under pressure thereto, means for operating said valves comprising a timer switch and switches individual to said valves whereby the latter may be operated selectively and successively lengthwise of said head under control of said timer switch, and manual control means for operating said valves independently of said timer switch comprising a main control switch connected in shunt with said timer switch and switches individual to said valves.

9. In a hydraulic log barker, means for supporting a log to be barked in substantially horizontal position and rotating it about its axis without endwise movement, a nozzle head extending lengthwise of said supporting means substantially parallel therewith and stationary lengthwise, said nozzle head having a plurality of juxtaposed jet openings disposed to project against the log a high pressure water jet extending lengthwise of the log with the areas of the jets from adjacent openings overlapping, valve means effective for opening and closing said jet openings individually and successively and thereby projecting against the log a high pressure water jet traveling along the log lengthwise thereof, and timer means for operating said valve means.

10. In a hydraulic log barker, means for supporting a log to be barked in substantially horizontal position and rotating it about its axis at substantially constant predetermined speed and without endwise movement, a nozzle head extending lengthwise of said supporting means substantially parallel therewith and stationary lengthwise, said nozzle head having a plurality of juxtaposed jet openings disposed to project against the log a high pressure water jet extending lengthwise of the log with the areas of the jets from adjacent openings overlapping, valve means effective for opening and closing said jet openings individually and successively and thereby projecting against the log a high pressure water jet traveling along the log lengthwise thereof, and means comprising timer means effective for operating said valve means in timed relation to the speed of rotation of the log.

HERBERT W. GUETTLER.
